UNITED STATES PATENT OFFICE.

EDWARD B. HESS, OF NEW YORK, N. Y., ASSIGNOR TO ROYAL TYPEWRITER COMPANY,
OF NEW YORK, N. Y., A CORPORATION OF NEW JERSEY.

TYPE-WRITING MACHINE.

993,681

Specification of Letters Patent. Patented May 30, 1911.

Application filed April 22, 1909. Serial No. 491,426.

To all whom it may concern:

Be it known that I, EDWARD B. HESS, a citizen of the United States of America, residing in the borough of Manhattan, city of New York, (post-office address, 136 Liberty street,) have invented certain Improvements in Type-Writing Machines, of which the following is a specification.

This invention relates to certain improvements in card guides and holders for front strike typewriting machines being an improvement upon the devices disclosed in the application of Lewis C. Myers No. 491,547 filed April 22, 1909.

15 In the accompanying drawings Figure 1, is a front elevation; Fig. 2, a plan view; Fig. 3, a side or end elevation; Fig. 4, a front elevation of the card holder detached; Fig. 5, a detail view showing the platen and 20 a special form of the front guide and paper or card holder mounted in rear of the platen and extending forward over it; Fig. 6, a like view showing the front part of this top paper holder folded back out of operative position; and Fig. 7, a detail enlarged section on the line 7, 7, of Fig. 1.

The drawings show a paper table *a*, paper pan *b*, rear feed rolls *c*, front feed rolls *d*, vertically movable scale *e* that may be moved 30 up to the line of print when the feed rolls are thrown off. The feed rolls are thrown away from the platen and the scale bar moved to the printing point when shaft *f* is partially rotated. The pivoted arms or levers carrying the feed rolls normally lie in transverse notches in the shaft and when the shaft is rotated they are forced up on the high part, that is to say, upon the periphery of the shaft and the feed rolls are then withdrawn from the platen.

35 *g* is a rotatable shaft operated through the release lever (not shown) to move the scale bar to the printing point at the time the feed rolls are thrown off, that is to say, *g* is a rock shaft having a forwardly projecting curved arm *g'* at each end and to the ends of which are pivoted upwardly extending arms *g''*, in the upper ends of which is carried the scale bar *e*.

40 *h* are hinged top clamps or guides adjustable along the transverse bar *h'* and extending forward from the rear over the platen and capable of being thrown rearwardly out of operation as indicated in Fig. 3, which

shows the left hand clamp or guide so adjusted. 55

i is the segment that has at each of its ends an aperture *i'* to receive pins *k* at the lower corners of the vertically disposed card clamp or guide *j*. 60

m indicates a well known form of type bar guide and *n* a well known form of ribbon vibrator located in rear of the guide.

Between the printing surface of the platen *o* and the rear of the ribbon vibrator is located the card holder *j* that may be appropriately mounted in any suitable way upon the machine, as, for instance, in the way shown in Fig. 1.

On the lower plate of the type bar guide *m* at each end or side thereof is an upright projection *r* that may be turned inwardly or rearwardly sufficiently to bear against the lower edge of the card holder *j* and hold it out of contact with the ribbon vibrator. 70

The card holder is shown detached in Fig. 4 in front elevation and in top plan in Fig. 2. It comprises a flat plate to which the letter *j* has been applied. Its upper edge has in it an oblong recess *s* of suitable width 80 and of sufficient depth to accommodate the type bar heads;—that is to say, to permit the type to make impact against the platen. To the right and left of this opening *s* the plate is formed with openings *t*, *t*, which are preferably triangular in shape, as shown, or otherwise, and the plate at the straight bottom edges of these openings is engraved 85 with a scale *u*. The small tongues or projections *t'* formed of the sheet metal of which the card holder plate is formed and projecting into the openings *t*, serve to prevent an inserted card envelop or sheet from entering either of the openings or striking against the edges or walls thereof. Beyond the flat 90 central portion of the plate having the openings *t*, *t*, the plate is formed with lateral extending wings *v* that are deflected to the front as seen in Fig. 2, the point of deflection or bend being indicated by the line *v'* 100 in Figs. 1 and 4.

An important feature of my construction is the arrangement of the recess *s* in the card holder plate,—that is to say, it is located at one side of the center thereof. This is 105 clearly seen in Fig. 1, where printing will occur close to the right hand edge of that recess the width of the recess being such as

to permit observation of several printed letters opposite the recess as well as others that may appear through the left hand one of the openings *t*. There is less covering of 5 the printed matter than would be the case if the recess *s* were centrally disposed.

The paper clamps *h* mounted upon the cross bar in rear of the platen so as to be adjustable longitudinally of the platen are 10 hinged so as to be thrown rearwardly into the position shown in Fig. 3. They each comprise the arm *h* having mounted in appropriate bearings in its front end the paper clamping roller *h*². This roller has a shaft 15 *h*³ turning in bearings in lugs turned up at the sides of the arm *h*. On this shaft is hinged a sheet metal finger or margin paper guide plate that is curved to conform to the front face of the platen and when down,— 20 that is, in operative position, as in Fig. 5; its lower edge overlaps and lies against the front face of the scale bar *e*. There is therefore, little, if any opportunity for an inserted card to pass to other than its proper position 25 in rear of the card holder *j*.

A flat spring *q* is attached by screw *q*' to the arm *h* and extends to the forward edge of the latter. Beneath the spring the arm has a slot *q*² whose rear wall is indicated by 30 the dotted line *q*³, Fig. 2, and which extends to the front edge of plate *h*. The hinged guide *p* has a curved finger *p*' extending rearwardly from its rear edge over the spring *q*' and the upward reaction of the 35 spring tends to hold the guide down in operative position. When the guide is turned up into inoperative position, the lip *p*' forces the spring down until the edge of the lip passes the center of motion when the reaction 40 of the spring tends to throw the guide up. With this arrangement an inserted card may be held closely against the face of the platen and printing may be done thereon very close to the top and bottom edges 45 thereof. If it is desired that the printing upon the card shall extend to the extreme side edges thereof, then the fingers or guides *p* may be moved upwardly on the front hinge portions. It is obvious, therefore, 50 that the guide finger *p*, and clamping member comprising the arm *h* may be moved upwardly together for any desired reason. When writing on side edges of cards or 55 paper the finger *p*, which serves primarily to guide the paper or card from the scale to the roll in arm *h*, may be folded back on its hinge over the arm *h* without raising the latter. The surface of the clamping member co-operating with the platen is shown as 60 a roll and is preferably such. The guide *p* is preferably sheet metal and is shown as such.

I claim:

1. A card holder for a visible typewriting machine adapted to be mounted in rear of

the ribbon vibrator adjacent the face of the platen and having an opening through which the type impinge against the platen the right hand edge of which opening crosses the printing line to the right of the printing 70 point and closely adjacent thereto and the left hand edge crosses the printing line a substantial distance to the left of a vertical line passing through the printing point.

2. A card holder for a visible typewriting 75 machine adapted to be mounted in rear of the ribbon vibrator adjacent the face of the platen and having an opening through which the type impinge against the platen the right hand edge of which opening crosses the 80 printing line to the right of the printing point and closely adjacent thereto and the left hand edge crosses the printing line a substantial distance to the left of a vertical line passing through the printing point, 85 and also having side wings extending from the central portion of the holder at each side obliquely forward.

3. A card holder for a visible typewriting 90 machine adapted to be mounted in rear of the ribbon vibrator adjacent the face of the platen and having an opening through which the type impinge against the platen the right hand edge of which opening crosses the 95 printing line to the right of the printing point and closely adjacent thereto and the left hand edge crosses the printing line a substantial distance to the left of a vertical line passing through the printing point, and also having side wings extending from the 100 central portion of the holder at each side obliquely forward and also having on each side of said opening another opening the bottom edge of which is equipped with a scale. 105

4. In a visible typewriting machine, the combination of a centrally disposed card holder mounted rigidly upon the frame and interposed between the printing surface of the platen and the ribbon vibrator, combined with margin clamps adjustable longitudinally of the platen and each composed of a forwardly extending arm adapted to be swung upwardly and rearwardly away from the platen and a clamping finger hinged in the front end of said arm bent to conform to the surface of the platen and extending across the front face thereof and adapted to be swung upwardly and rearwardly out of 110 operative position. 115

5. In a visible typewriting machine, a margin paper clamping and guiding device comprising a paper clamping member co-acting with the platen above the printing line out of the paths of the type when they are making an impression and a paper guide movably attached above the line of print to the clamping member and extending downward across the printing line and mounted 120 and adapted to be moved away from the 125 13

printing line without throwing the clamp out of operation.

6. In a visible typewriting machine, a margin paper clamping and guiding device comprising a paper clamping member co-acting with the platen above the printing line out of the paths of the type when they are making an impression, a paper guide movably attached above the line of print to the clamping member, and extending downward across the printing line and mounted and adapted to be moved away from the printing line without throwing the clamp out of operation and a paper scale located 15 below the line of print and overlapped by the guide.

7. In a visible typewriting machine, a paper clamp and guide adjustable longitudinally of the platen and traveling therewith 20 extending forward over the platen and having a clamping member co-acting with the platen above the printing line and an end portion, acting as a paper guide, extending around the platen below the printing line 25 and mounted to be moved out of the way so as not to be struck by the type without throwing the clamping member out of operation.

8. In a visible typewriting machine, a paper clamp and guide adjustable longitudinally of the platen and traveling therewith 30 extending forward over the platen and having a clamping member co-acting with the platen above the printing line and an end portion, acting as a paper guide, extending 35 around the platen below the printing line and mounted to be moved out of the

way so as not to be struck by the type without throwing the clamping member out of operation combined with means, stationary 40 with respect to the traverse of the carriage, acting to hold a sheet at the printing point.

9. In a visible typewriting machine, a paper clamp and guide adjustable longitudinally of the platen and traveling therewith 45 extending forward over the platen and having a clamping member co-acting with the platen above the printing line and an end portion, acting as a paper guide, extending around the platen below the printing line 50 and mounted to be moved out of the way so as not to be struck by the type without throwing the clamping member out of operation, combined with a scale, also traveling 55 with the platen, located below the line of print and overlapped by the paper guide.

10. In a visible writing machine, paper clamping and guiding devices comprising a revoluble transversely movable platen, a paper clamping member co-acting with the 60 platen on one side of the printing line out of the paths of the types and a paper guide extending across the printing line and mounted and adapted to be moved out of the paths of the types without throwing the clamping 65 member out of operation, combined with a scale located on the other side of the printing line and overlapped by the paper guide.

In testimony whereof, I have hereunto
subscribed my name.

EDWARD B. HESS.
